[57] CLAIM

The ornamental design for a refillable inkmarker, as shown and described.

DESCRIPTION

FIG. 1 is a right side elevational view of a refillable inkmarker showing my new design with the cover being shown thereon, the left side elevational view being a mirror image thereof;

FIG. 2 is a left end elevational view thereof;

FIG. 3 is a right end elevational view thereof;

FIG. 4 is a right side elevational view in an exploded condition, the left side being a mirror image thereof; FIG. 5 is a right side elevational view of a refillable inkmarker showing my new design according to a second embodiment with the cover being shown thereon, the left side elevational view being a mirror image thereof;

FIG. 6 is a left end elevational view of the second embodiment;

FIG. 7 is a right end elevational view of the second embodiment; and,

FIG. 8 is a right side elevational view of FIG. 5 in an exploded condition, the left side being a mirror image thereof.

FIG. 3

FIG. 1

FIG. 2

FIG. 4

FIG. 7

FIG. 5

FIG. 6

FIG. 8
